UNITED STATES PATENT OFFICE.

RUDOLF A. BENDER AND WILLIAM F. SCHOMBURG, OF SAN ANTONIO, TEXAS.

SPARK-ARRESTER.

No. 890,015.

Specification of Letters Patent.

Patented June 9, 1908.

Application filed November 18, 1907. Serial No. 402,674.

To all whom it may concern:

Be it known that we, RUDOLF A. BENDER and WILLIAM F. SCHOMBURG, citizens of the United States, residing at San Antonio, in 5 the county of Bexar and State of Texas, have invented certain new and useful Improvements in Spark-Arresters, of which the following is a specification.

This invention pertains to certain new and 10 useful improvements in spark arresters, and has for its object to provide a device of this type which will be efficient and practical in its use and of simple cheap construction.

Further objects of the invention will appear 15 in the course of the following specification.

Referring to the accompanying drawings forming a part of this specification and in which like characters of reference denote 20 similar parts throughout the several views, Figure 1 is a vertical sectional view taken through a chimney or smoke stack and showing the containing casing in section and the remaining parts in side elevation, and Fig. 2 is a like view showing all of the parts in section.

In the drawings 1 designates the chimney or smoke stack which is arbitrarily depicted.

2, designates a cylinder which forms the 30 main part of the containing casing, the upper end of which is inclined as at 3. The lower end of the casing is also inclined as indicated at 4, and has an outwardly extending flange 5.

6 designates a section of tubing which fits 35 into the inside of the stack and is formed with a right angular outwardly projecting flange 7 which seats on the top edge of the stack. The base flange 5 of cylinder 2, seats on flange 7 and is riveted thereto.

40 8 designates a second cylinder which is formed adjacent its lower end with a peripheral flange 9 seating on the top edge of cylinder 2 and is thereby held in position. The lower end of cylinder 8 projects somewhat on 45 the interior of cylinder 2 and forms a guide for a ring 10, which has a sliding movement therein.

The invention contemplates imparting a 50 spiral motion to the egressing smoke, to attain which we employ coils of tubing 11, which are spirally wound and having the coils, united to form a practically integral structure. Each of the upper and lower coils are cut through at right angles to the axis of

the coils as a whole so as to leave the top and 55 bottom thereof completely open. The bottom of the coil of tubing is flanged slightly outwardly as at 12, so as to completely cover the upper end of tube 6, and thereby assure the passage of all of the smoke through the coil. 60 Located directly above the open end of the top of the coil is a deflector 13 formed cone-shaped on its under face and being provided with a perforation 14. A series of links 15 are employed which pass through the deflector 13 and are rigidly secured thereto and which at their top and bottom ends are affixed to the ring 10 and the coil 11 respectively. At the lower portion of the stack a lever 16 is pivoted, one end of which is connected to a wire rope 17 which extends upwardly through aperture 14 in deflector 13 and also through the space 18 formed between the coils at the center thereof up and over a pulley 19 carried by the cylinder 8 and 70 thence downwardly and secured to the top of deflector 13. To the other end of lever 16 is connected a wire rope 20 which has its upper end secured to the bottom of coil 11. It will thus be seen that by moving the lever 16 the 80 coil 11 will be raised or lowered as desired to enable the stack to be cleaned.

In conjunction with the above we employ a brush 21 which is movable vertically along the length of the stack by means of a chain 85 22 which has its ends secured to said brush and which passes over sprockets 23 24, located at the upper and lower ends of the stack respectively. As shown in dotted lines in the drawings at 25 the sprocket 24 exterior the stack is equipped with a crank handle by means of which the sprocket may be rotated to move the brush along the length of the stack.

In operation the smoke will be encountered by the lower open end of coil 11, and which in passing through the coil will be given spiral movement. When the smoke egresses through the top end of coil 11 it will be deflected outwardly by the deflector 13 100 thereby projecting sparks and cinders against the cylinder 2 due to the centrifugal force which the smoke has acquired during its passage through coil 11. The cinders and other particles will gravitate downwardly and will 105 be caught between the flange 12 at the base of the coil and the inclined portion 4 of cylinder 2. To release the collected particles,

proper movement of lever 16 will raise coil 11, and thus permit the collected matter to gravitate downwardly through the stack.

What we claim is:—

5 1. In combination with a stack, a tube received in the upper portion thereof and formed with a flange seating on the top, a cylinder having inclined ends, a flange secured to one of said ends and secured to said 10 first named flange, a second cylinder having a peripheral projection received in the top end of the first cylinder and having its projection seating on the end thereof, a guide ring in said second cylinder, a coil of tubing 15 open at the top and bottom thereof, a deflector having a cone-shaped under face overlying the top end of said coil of tubing, links connecting said coil of tubing, said deflector and said guide ring, and means connected to 20 said deflector to raise and lower the parts.

2. In combination with a stack, a cylinder thereon, a second cylinder of less diameter than the first secured to said first cylinder, a guide ring in the second cylinder, a coil of 25 tubing having its top and bottom open, the bottom of said coil engaging the base of the first cylinder and forming a closure therefor, means for connecting said coil to said guide ring, and means for raising and lowering said

coil said ring acting as a guide for said coil in its up and down movement.

3. In combination with a stack a cylinder thereon, a second cylinder of less diameter than the first secured to the top of the latter, a coil of tubing open at its top and bottom, a 35 deflector overlying the top of said coil and spaced therefrom, a guide ring slidingly mounted in said second cylinder, links connected at their tops to said ring and at their bottoms to the top of said coil of tubing, said 40 links extending through said deflector and being connected thereto, a pulley in the second cylinder, a lever pivoted at the base of the stack, and a pair of cables one of which is connected to one end of said lever and to the 45 base of said coil of tubing and the other of which is connected to the other end of said lever passes upward through the central space between the coils then through said deflector over said pulley and finally secured 50 to said deflector.

In testimony whereof we have affixed our signatures in presence of two witnesses.

RUDOLF A. BENDER.

WILLIAM F. SCHOMBURG.
